SERVING TRAY OR THE LIKE

Caroline A. Conrath, 109½ Collins Ave.,
Mandan, N. Dak.

Filed Aug. 14, 1962, Ser. No. 71,282

Term of patent 14 years

(Cl. D44—10)

FIG. 1.

FIG. 4.

FIG. 2.

FIG. 3.

FIGURE 1 is a perspective view of a serving tray or the like showing my new design;

I claim:

The ornamental design for a serving tray or the like, as shown.
